UNITED STATES PATENT OFFICE

2,496,068

BED GUARD

Valentine W. Rutkowski, Rockville Centre, N.Y.

Application April 13, 1949, Serial No. 87,282

3 Claims. (Cl. 5—331)

1

This invention relates generally to bed guards and the subject matter of this application is closely related to the subject matter disclosed in applicant's pending application for patent filed September 13, 1948, under Serial No. 48,968.

A primary object of this invention is to provide a detachable, universal type bed guard, the function of which is to protect the occupant of the bed from falling out of the bed while asleep, the bed guard being particularly useful for use with children, invalids and certain other persons who may find such protection necessary.

Another object of the invention is to provide a bed guard construction which is particularly well adapted for mounting upon a bed having an angle iron bed rail or a box-spring type bed, and the said angle iron bed rail or analogous member is an element in the combination of elements proposed by this invention, whether it be part of the original bed or a part which is added according to this invention, and it should also be carefully noted that the bed guard constructed according to this invention can also be used with a conventional wooden bed rail.

Another object of this invention, directly relating to the last part of the preceding object, is to provide a bed guard construction including a replaceable spacer block which may be constructed to have a thickness particularly adapted to facilitate the connection of the bed guard on a particular bed, the bed spacer block being entirely removable when the bed guard is used with a bed having a wooden rail.

Still another object of this invention is to provide a bed guard including a flat plate which can be removed to adapt the bed guard for use with particular types of bed rails, as for example a bed rail of angle iron construction having the vertical flange depending from the outside edge of the rail.

And a last object to be mentioned specifically is to provide a bed guard which is inexpensive to manufacture, simple and versatile in use, and generally adapted to provide durable and efficient service.

With these objects definitely in view, this invention resides in certain novel features of construction, combination and arrangement of elements and portions as will be hereinafter described in detail in the specification, particularly pointed out in the appended claims, and illustrated in the accompanying drawing which forms a material part of this application, and in which:

Figure 1 is a three dimensional view of a portion of an upright in this bed guard and operatively associated with an angle plate as provided

2

for combination with a box-spring mattress, which latter is shown fragmentarily in the view;

Figure 2 is a vertical sectional view taken on the irregular section line 2—2 in Figure 1;

Figure 3 is a three dimensional view of a complete bed guard, with the spacer blocks removed and shown as mounted upon a bed having a wooden bed rail;

Figure 4 is a three dimensional view showing how an upright of the bed guard can be secured to an angle iron bed rail having a vertical flange extending upwardly from its outer edge; and

Figure 5 is a similar view showing how the device can be secured to an angle iron bed rail having its vertical flange depending from its outer edge, it being noted that the member hereinafter referred to as the flat metal plate on the lower end of the upright being removed when the device is used, as illustrated in both Figures 4 and 5.

Similar characters of reference designate similar or identical elements and portions throughout the specification and throughout the different views in the drawing.

Referring now to the drawing in detail, this invention is used with bed structures of different types, Figure 1 representing how a box-spring mattress, generally indicated by the numeral 10, and including ordinarily a wooden frame member 12, will be provided according to this invention with an angle plate having a horizontal flange portion 14 and a vertical flange portion 16, the vertical flange portion 16 being secured as by wooden screws 18 on the wooden frame member 12, it being preferred that spacer members 20 will be inserted between the flange 16 and the side of the box-spring mattress, as indicated best in Figure 2.

The bed guard, indicated generally at 22, will include a pair of uprights 24 and elongated horizontal members 26 secured to and between the uprights 24. The lower end portion 28 of each of the uprights 24 is formed with a recess 30 on the side of the upright adjacent the mattress 10, and a flat plate 32, ordinarily metallic but not necessarily so, will be secured as by wood screws 34 to the lower end portion 28 of the uprights, so as to extend over the recess 30, the lower portion of the plate 32 being parallel to the adjacent face of the recessed portion of the uprights, whereby a vertical slot is provided in the bottom end of each upright. A spanner bolt 36 is inserted through aligned apertures in the lower portion 28 of the upright and the flat plate 32, the spanner bolt having a head 38 and a wing nut

40, the latter being disposed toward the side of the upright remote from the mattress 10.

A replaceable spacer block 42, also apertured to receive the spanner bolt 36 is removably securable in the vertical slot or recess 30 and may be made to bear against one side of the flange 16 while the lower end of the flat plate 32 bears against the other side of this same flange.

In an alternative usage of this invention, the spacer block 42 is removed when the device is used with a wooden bed rail 44 as indicated in Figure 3. The upwardly extending flange 46 of angle iron bed rails may be clamped directly between the spacer block 42 and the lower end portion 28 of the upright, as clearly indicated in Figure 4. Furthermore, the flat plate 32 may be removed to adapt the device for use with a bed rail having a downwardly extending flange 48, as indicated in Figure 5.

It will be clear that all the above recited objects of this invention can be amply achieved by the disclosed novel structure and further description appears to be unnecessary.

Having described the invention, what is claimed as new is:

1. In a bed guard having uprights and horizontal members connected to and between the uprights, means for mounting each upright comprising an elongated angle plate securable on the side of a bed and having a vertical flange, a recess in the lower end portion of the upright and on the side thereof adjacent said angle plate, a flat plate rigidly secured to an intermediate portion of the upright and extending downwardly over said recess, a replaceable spacer block within said recess, and means for clamping said block and a part of said vertical flange in said recess so as to support the upright.

2. A bed guard according to claim 1 wherein

said means for clamping comprises aligned apertured portions in each flat plate and the lower portion of the upright and spacer block associated therewith, and an elongated spanner bolt inserted through said apertures.

3. The combination, with a box spring mattress having a frame member extending along a bottom edge thereof, of a bed guard comprising a plurality of uprights connected by horizontal members, and means securing each upright to said mattress, said securing means comprising an angle member having a vertical flange, a spacer member interposed between said frame member and said vertical flange, a threaded element extending through said flange and the associated spacer member into said frame member, each of said uprights having a recess in the lower end portion thereof, a plate secured to the upright and extending over said recess, a replaceable spacer block in said recess, and a threaded member extending through said lower portion, spacer block and flat plate and clamping said upright flange between said plate and the associated spacer block.

25 VALENTINE W. RUTKOWSKI.
